COMBINED REFLECTOR AND HOUSING FOR
TABLE LAMP OR THE LIKESidney Gibson, Suite 110, 57 Godstone Road,
Willowdale, Ontario, Canada

Filed June 29, 1970, Ser. No. 23,692

Term of patent 14 years

Int. Cl. D26—05

U.S. Cl. D48—20

FIG. 2

FIG. 1 is a perspective view showing the top and sides of a combined reflector and housing for a table lamp or the like showing my new design;

FIG. 2 is a second perspective view thereof showing the bottom and opposite sides.

I claim:

The ornamental design for a combined reflector and housing for table lamp or the like, as shown.
